UNITED STATES PATENT OFFICE.

MONROE B. HAINES, OF SANDUSKY, OHIO, ASSIGNOR TO THE ERIE RUBBER CORPORATION, OF SANDUSKY, OHIO, A CORPORATION OF OHIO.

DESIGN FOR A TIRE.

Application filed April 14, 1924. Serial No. 9,247. Term of patent 14 years.

To all whom it may concern:

Be it known that I, MONROE B. HAINES, a citizen of the United States, residing at Sandusky, in the county of Erie and State of Ohio, have invented a new, original, and ornamental Design for a Tire, of which the following is a specification, reference being had to the accompanying drawings, which form a part thereof, and in which—

Figure 1 is a front view of a tire showing my new design, while

Figure 2 is a sectional view of the tire shown in Figure 1, taken on the line 2—2 of Figure 1.

I claim:

The ornamental design for a tire substantially as shown.

MONROE B. HAINES.
